UNITED STATES PATENT OFFICE.

ARTHUR NUTT, OF KENMORE, NEW YORK, ASSIGNOR TO CURTISS AEROPLANE & MOTOR COMPANY, INC., A CORPORATION OF NEW YORK.

VALVE-OPERATING MECHANISM.

Refile for abandoned application Serial No. 9,166, filed February 14, 1925. This application filed February 14, 1927. Serial No. 168,205.

My invention relates to valve operating mechanism for internal combustion motors and is concerned more particularly with a valve tappet arrangement in which the several valve tappets are so formed and so related to the intake valves and to the exhaust valves of the motor as to admit of the proper operation of said valves, even tho such valves are disposed respectively at opposite sides of a plane passing thru the axes of the motor cylinders, by means of devices movable about an axis common to the total number thereof. Preferably, each valve tappet includes a stem portion and a head portion extending off from said stem portion at substantially a right angle, said head portion, intermediate of its free end and said stem, having formed thereon a bearing surface upon which one of the actuating devices is adapted to act.

20 In the drawings, wherein like reference characters denote like or corresponding parts,

Fig. 1 is a side elevation of the valve operating mechanism of one cylinder of a multi-cylinder internal combustion motor, the cylinder block or casting being shown in section;

Fig. 2 is an end view of the valve operating mechanism; the cam shaft of the cylinder block or castings being shown in transverse section;

Fig. 3 is a plan view of the mechanism illustrated in Fig. 1;

Fig. 4 is a plan view, similar to Fig. 3, of a modification; rocker arms as distinguished from the cam shaft being shown as the valve operating means;

Fig. 5 is a view similar to Fig. 1, further illustrating said modification, and

Fig. 6 is an end view of such modification.

40 In the embodiment of the invention illustrated in Figs. 1 to 3, inclusive, 10 designates the cylinder block or casting within which the cylinders 11 of the motor (but one of which is shown) are formed. Preferably, 45 the cylinders 11 are cast en bloc. Each cylinder 11 is provided with an exhaust valve port 12, and an intake valve port 13, said ports being so formed in the cylinder casting as to open outwardly and oppositely as indicated in Figs. 2 and 3. Viewed in plan, the intake and exhaust ports 12 and 13 are so related one to the other and to the cylinder casting as to overlap or extend beyond the plane of the axes of the motor cylinders, such

an overlap being conducive to maximum port area where only two valves per motor cylinder are used. In high speed motors, and especially in aeronautical internal combustion motors, maximum port area is most desirable. Heretofore, to provide for the proper operation of the intake and exhaust valves of a motor having its ports thus formed, separate cam shafts have been provided for each cylinder block or casting, the one cam shaft being adapted to operate the one set of valves and the other cam shaft the other set of valves in view of the fact that such valves are disposed respectively at opposite sides of the plane above mentioned. In the present invention, instead of providing separate cam shafts for each set of valves, but a single cam shaft is provided. Such shaft is designated as 14, while the cams fastened to or formed upon it are designated as 15; a separate cam being provided for each valve regardless of the total number thereof.

The valves of the motor are of more or less conventional construction. The exhaust valves 16 have the stem portions thereof extended thru or beyond the cylinder head block, as have also the intake valves 17. In view of the port arrangement, however, the stems of the exhaust valve 16 are extended thru the cylinder head block at one side of the plane of the axes of the cylinders, whereas the stems of the intake valves 17 are similarly extended on the opposite side of said plane, and as the cam shaft is disposed symmetrically with respect to said plane, obviously the valve stems are arranged respectively at opposite sides of the cam shaft.

To admit of the proper operation of the valves thus opposed, valve tappets 18 are provided. Each tappet includes a stem or shank portion 19, a head portion 20 and a bearing surface 21, said head portion 20 being extended off from the stem portion at substantially a right angle to overlap, extend beyond and consequently intersect the plane of the motor cylinder axes. Bearing surface 21 is preferably of arcuate form and is formed upon the head portion of the valve tappet at a point near its juncture with the stem. An appropriate guide 22 is provided for each valve tappet.

105 It will be seen from the above, taken in connection with the accompanying drawing, that the valve tappets, while identical in form,

have their head portions extended oppositely; one group or set being extended away from the valve stems thereof in one direction, whereas the other group or set extend away from the valve stems thereof in the opposite direction; such an arrangement causing the bearing surfaces of the total number of tappets to line up longitudinally of the motor directly beneath the operating cam shaft 14.

10 In the modification of Figs. 4 to 6, inclusive, the valve arrangement is exactly as in the preferred embodiment of the invention illustrated in Figs. 1 to 3. In said modification, however, instead of a single cam shaft being provided to actuate the valve tappets and consequently the valves, rocker arms 23 are used. The rocker arms 23 are in each instance identical, and in each instance are so arranged as to move, during the operation of the motor, 20 about an axis common to the total number thereof; the tappet engaging end of each rocker arm engaging the tappets in the plane of the motor cylinder axes. Thus arranged, the rocker arms are interchangeable, as are the valve tappets; such interchangeability being conducive to simplicity of construction and reduced production cost. The operating means for the rocker arms, designated as 24, notwithstanding the fact that the valves are 30 arranged as indicated, necessitates the provision of but a single cam shaft (not shown).

While I have described my invention in detail in its present preferred embodiment, it will be obvious to those skilled in the art after 35 understanding my invention, that various changes and modifications may be made therein without departing from the spirit or scope

thereof. I aim in the appended claims to cover all such modifications and changes.

What I claim is:

1. In valve operating mechanism for internal combustion motors, a valve tappet including a reciprocal stem portion and a rigid head portion reciprocal with said stem portion and extending off therefrom substantially a right angle, a guide for said stem portion disposed at one side of a plane passing thru the axis of the cylinder with which said valve tappet is associated, said head portion being extended across and beyond said plane, a valve operable under the action of said head portion, said valve being disposed on the opposite side of said plane from said guide, and an operating means for the valve tappet engageable with said head portion intermediately of its 45 free end and said stem.

2. In valve operating mechanism for internal combustion motors, an intake valve and an exhaust valve disposed respectively at opposite sides of the plane of the axis of the 60 motor cylinder which said valves collectively serve, valve tappets, one for each valve, each tappet including a reciprocal stem portion and a head portion reciprocal with said stem portion and extending off therefrom at an angle, said valve tappet stems being likewise disposed respectively at opposite sides of the plane of said cylinder axis, and an operating means common to the total number of valve 65 tappets and engageable with said head portions to actuate said valves.

In testimony whereof I hereunto affix my signature.

ARTHUR NUTT
